United States Patent Office

Des. 185,963

Patented Aug. 25, 1959

185,963

LOUDSPEAKER CABINET

Charles Eames, Pacific Palisades, Calif., assignor to
Stephens Tru-Sonic Inc., Culver City, Calif., a corpora-
tion of California

Application May 20, 1957, Serial No. 46,232

Term of patent 14 years

(Cl. D26—14)

FIG. 1.

FIG. 2.

FIG. 3.

Fig. 1 is a front perspective view of the loudspeaker cabinet showing my new design;

Fig. 2 is a reduced side elevational view; and

Fig. 3 is a reduced front elevational view thereof.

The side not shown is the same in appearance as the side shown. The back of the article is substantially plain.

I claim:

The ornamental design for a loudspeaker cabinet, as shown and described.
